UNITED STATES PATENT OFFICE.

DICKERSON G. BAKER, OF WILLIMANTIC, CONNECTICUT, ASSIGNOR TO THE WILLIMANTIC LINEN COMPANY, OF SAME PLACE.

THREAD-WINDER.

SPECIFICATION forming part of Letters Patent No. 642,281, dated January 30, 1900.

Application filed June 13, 1898. Serial No. 683,249. (No model.)

To all whom it may concern:

Be it known that I, DICKERSON G. BAKER, a citizen of the United States, and a resident of Willimantic, in the county of Windham 5 and State of Connecticut, have invented certain new and useful Improvements in Thread-Winders, of which the following is a full, clear, and exact description, whereby any one skilled in the art can make and use the same.

10 My invention relates to the class of devices used for building up a mass of thread on a core; and the object of my invention is to provide a device of this class which may be run at a comparatively high rate of speed, 15 thus increasing the capacity of the device, and one in which the character of the work produced shall be of a comparatively high grade.

To this end my invention consists in the 20 device as a whole, in the combination of parts, and in the details and their combination, as hereinafter described, and more particularly pointed out in the claims.

Referring to the drawings, Figure 1 is a 25 top or plan view of a machine embodying my invention with parts broken away. Fig. 2 is a view in side elevation of the same with parts cut in central section. Fig. 3 is a detail end view in section through the traverse- 30 drum on the line $x-x$ of Fig. 2. Fig. 4 is a diagram view illustrating the relative position of the parts at a preliminary step in the winding operation. Fig. 5 is a like view illustrating the relative position of the parts 35 at a more advanced stage in the operation of winding.

In the operation of winding thread, as on a bobbin or the like, prior to my invention a difficulty has been experienced in attempts 40 to run the spindle at a high rate of speed, in the tendency of the thread to jump, and a consequent loosening thereof between the guide and the bobbin, the proper tension on the thread to produce desired results in the 45 finished bobbin being insufficient to prevent such jumping and consequent loosening. An objectionable result of this action is a bobbin less compactly wound than where the tension of the thread is preserved at all times, the 50 lay being uneven and a bobbin being pro-

duced having an uneven surface at the end thereof.

In the within-described device means are provided whereby an even tension is preserved at all points along the length of thread 55 to the point of its delivery onto the bobbin, and the machine may be run at an extremely high rate of speed without any lessening of the tension or any jumping of the thread.

In the accompanying drawings there is 60 illustrated a form of device for practicing the invention, in which the letter a denotes legs or supports, upon which is mounted a table b . A driving-shaft c , carrying a driving-pulley c' , is borne in the supports a , a belt c^2 extending 65 from the pulley c' to a traverse-pulley d' , located on the traverse-shaft d . This traverse-shaft is mounted in standards b' on the table b and also is supported at one end by a traverse-drum standard g . A gear d^2 is secured 70 to one end of the traverse-shaft and is in mesh with a winding-gear e' on the winding-spindle e . The opposite end of the traverse-shaft bears traverse-drum pinions d^3 , in mesh with gear-teeth f' , formed on the outer surface of the traverse-drum f . 75

A sleeve g' is mounted in the traverse-drum standard g and has a rotary movement therein, this sleeve projecting on opposite sides of said traverse-drum standard. Traverse-drum cases g^2 are secured at each end of the sleeve g' in any suitable manner, in the form shown the cases being split on one side, and clamping-bolts g^3 , as shown in dotted outline in Figs. 3 and 4 of the drawings, are 80 employed to clamp the cases tightly upon the sleeve g' . These cases surrounding the traverse-drum have recesses g^4 receiving that portion of the drum bearing the gear-teeth f' . Collars f^2 are clamped to the drum close to 85 each of the cases for preventing endwise movement of the drum therein. The traverse-drum pinions d^3 are located in pinion-recesses g^5 in the lower side of each of the cases, and plates g^6 g^7 , located outside of the 90 gear-teeth f' and traverse-drum pinions d^3 , close the recesses g^4 and g^5 , respectively. 95

The winding-spindle e is arranged to hold a core h , usually formed of paper, upon which the thread is to be wound. A guide-slot i is 100

formed through the wall of the traverse-drum *f*, this slot extending in a helical path for a portion of the way only about the drum and then in another helical path in the opposite direction about the drum to a point on a circumferential line coincident with the starting-point. The drum is caused to revolve with especial reference to the revolutions of the winding-spindle, and the guide-slot in the drum may be formed to cause the thread to travel from end to end of its path on the winding-spindle any desired number of times in a single revolution of said drum, the variation of this guide-slot or the changing of the relative rotation of the drum and spindle producing a variety of "winds" on the bobbin built up on the core supported on the spindle.

A bridge *l* extends through the drum from end to end, this bridge being supported at each end of the traverse-drum cases *g*² and lying close against the inner surface of the drum and in such position that a thread *m* passing through the slot passes over the edge 25 of the bridge to the winding-spindle.

It is preferred to rotate the traverse-drum in a direction to cause the guide-slot to continually exert pressure on the opposite side of the thread from that resting against the 30 bridge.

A tension-support *n* is secured in proper position to cause the tension *n*², borne on the tension-arm *n'*, to move the drum to one side out of its normal position, a spring *n*³ or like 35 device being employed to hold the tension continually in engagement with the surface against which it bears. In the form shown the tension *n*² bears against the casing within which the drum is located and on that side 40 of a line drawn through the axes of the winding-spindle and the driving-shaft of the traverse-drum opposite to that from which the thread is being led through the guide-slot in the drum. This pressure of the tension causes 45 the drum to be tilted to one side on the pivot formed by the sleeve *g*', causing the bridge or inner surface of the drum to lie continually in contact with the mass of thread being built up on the core on the winding-spindle.

50 In the operation of winding, the thread *m* passes through the guide-slot *i* in the traverse-drum *f*, over the front edge of the bridge *e*, and then backward toward the rear edge thereof onto the bobbin. The traverse-drum is preferably rotated in a direction to exert 55 pressure upon the thread and press against the edge of and toward the back of the bridge, in the device shown this result being produced by rotating the drum in the same direction as the winding-spindle. If the bridge should not be used, a like pressure on the thread may be caused by rotating the tension-drum in an opposite direction from that in which the winding-spindle is rotated.

I claim as my invention—

1. In machines for winding thread or the like, a traverse-drum with means for rotating it, a guide-slot extending through the wall of the drum, and a cop-holder located within the drum.

2. In a machine for winding thread or the like, a traverse-drum with means for rotating it, a guide-slot extending through the wall of the drum, a cop-holder located within the drum, and means for holding the inner surface of the drum adjacent to the cop-holder.

3. In machines for winding thread or the like, a rotary traverse-drum, means for rotating said drum, a guide-slot extending through the wall of the drum, and a winding-spindle located within the drum with means for rotating said spindle.

4. In machines for winding thread or the like, a rotary traverse-drum, a traverse-shaft operatively connected with the drum, means for rotating said shaft, a winding-spindle located within the drum and operatively connected with the traverse-shaft, and a guide-slot extending through the wall of the traverse-drum.

5. In machines for winding thread or the like, a winding-spindle, means for rotating the spindle, movable supports, a traverse-drum mounted on the supports and surrounding the spindle, means for rotating the drum, a guide-slot extending through the wall of the drum, and means for holding the supports in position with the inner wall of the drum adjacent to the winding-spindle.

6. In a machine for winding thread or the like, a winding-spindle, means for rotating the spindle, a traverse-drum surrounding the spindle, means for rotating the traverse-drum, a bridge located within the drum, and a guide-slot extending through the wall of the drum.

7. In machines for winding thread or the like, a winding-spindle, means for rotating the spindle, movable supports, a traverse-drum mounted on the supports, means for rotating the drum, a bridge located within the drum, a guide-slot extending through the wall of the drum, and means for holding the supports with the bridge in contact with the cop being formed.

8. In machines for winding thread or the like, a cop-holder, a traverse-drum surrounding the holder, a guide-slot extending through the wall of the drum, means for rotating the drum, and means interposed between the holder and drum and in engagement with the thread being wound.

9. In a machine for winding thread or the like, a traverse-shaft with means for rotating it, a winding-spindle operatively connected therewith, a sleeve surrounding the traverse-shaft and forming a bearing therefor, traverse-drum supports secured to said sleeve, a traverse-drum operatively connected with the

traverse-shaft, and a guide-slot extending through the wall of the traverse-drum.

10. In a machine for winding thread or the like, a cop-holder, a traverse-drum surrounding the holder and mounted on a supporting pivot, and a tension device exerting pressure to hold the drum at one side of a line pass-

ing through the axis of its pivot and the cop-holder.
